HOLDER FOR A DRY SHAVER

Florian Seiffert, Glashütten, Taunus, Germany, assignor to Braun A.G., Frankfurt am Main, Germany

Filed June 8, 1970, Ser. No. 23,353

Claims priority, application Germany Dec. 12, 1969

Term of patent 14 years

Int. Cl. D3—99

U.S. Cl. D87—1

Fig 1

Fig 5

FIG. 1 is a front elevational view of a holder for a dry shaver showing my new design;

FIG. 2 is an end elevational view thereof;

FIG. 3 is a rear elevational view, opposite relative to FIG. 1;

FIG. 4 is a top plan view thereof; and

FIG. 5 is a bottom plan view thereof.

I claim:

The ornamental design for a holder for a dry shaver, substantially as shown.
